UNITED STATES PATENT OFFICE.

ULYSSES D. KENWORTHY, OF ZIM, MINNESOTA.

MARKER.

1,088,591.

Specification of Letters Patent.

Patented Feb. 24, 1914.

Application filed November 26, 1912. Serial No. 733,662.

To all whom it may concern:

Be it known that I, ULYSSES D. KENWORTHY, a citizen of the United States, residing at Zim, in the county of St. Louis and 5 State of Minnesota, have invented new and useful Improvements in Markers, of which the following is a specification.

This invention relates to a marker designed for use in connection with railroad 10 tracks to indicate a line in parallelism to the track and spaced therefrom at any desired distance to serve as a guide for the usual dressing or cutting of the grass and weeds.

The main object of the present invention is 15 the provision of a marker adapted for coöperation with a railway track and to be drawn along the same by hand, the construction including an adjustable marking element whereby a line may be drawn on 20 the ground at any desired distance from and in parallel relation with the track.

The invention in its preferred form of 25 details will be described in the following specification, reference being had to the accompanying drawing, in which:—

Figure 1 is a plan view of the improved marker with parts in section, showing it applied; and Fig. 2 is an edge view of the marker with parts shown in section.

Referring particularly to the accompanying drawings, the improved marker comprises a substantially V-shaped section 2 connected at the ends remote from its apex by a brace bar 3. The terminals of the side bars 30 of the section 2 which extend beyond the brace bar are bent and formed to provide hooks 4 of a size and shape to slidably engage the ball of a railroad rail, as 5. Secured to the brace bar 3 at a central point 35 of the latter and extending through a loop 6 arranged at the apex of the V-shaped section is a hollow guide bar 7 in which is slidably mounted an adjustable section 8, the set screw 9 serving to secure the section 40 8 in longitudinal adjusted relation to the guide bar 7. The free end of the section 8 is bent laterally to provide a pointer bar 10, which pointer bar is of hollow construction,

as at 11, and slidably receives a marking element 12, having a size to permit its projection beyond the free end of the pointer bar, clamps or set screws 13 securing the marking element in adjusted relation in such pointer bar. Secured to one of the side bars of the frame section 2 are bracket plates 14, between which is pivotally mounted a handle member 15.

In the use of the device, the hooks 4 are engaged with one rail of a railroad track, the marking element, held through the adjustments described is arranged so that the operative end thereof is at the desired distance from the particular rail, and the marker as an entirety is drawn lengthwise the rail through the medium of a handle 15, the desired marking thus obtained affording a line between which and the rail the usual dressing or cutting of the grass and weeds is carried out.

The device may be readily applied to the track when desired for use or removed therefrom in a simple, expeditious manner by a single operator when necessary, as to avoid a passing train, and in use will, through the efforts of a single workman, provide a line 75 of guidance as rapidly as the device can be moved lengthwise the track.

The device is also useful in lining out ditches or similar railroad improvements as by the adjustment of the marking element 80 the same device can be used to mark an inner and outer line of cut.

What is claimed is:—

1. A marker for railroad use including a V-shaped section, a hollow bar fixed therein, 85 a section telescopically mounted in the hollow bar, said section having a downwardly projecting hollow terminal, a marking element telescopically mounted in the hollow terminal, and hooks carried by the V-shaped 90 section to engage a railroad track.

2. A marker for railroad tracks including a V-shaped section having hooks to slidably engage a railroad rail, a hollow guide bar secured in the section and projecting 95 through and beyond the apex thereof, an

adjustable section telescopically mounted in the guide bar and having a downwardly projecting hollow terminal, set screws passing through the guide bar to secure the adjustable section, a marking element telescopically mounted in the hollow terminal, and set screws carried by said terminal to engage the marking element and secure the

latter in adjusted position in said hollow terminal.

In testimony whereof I affix my signature in presence of two witnesses.

ULYSSES D. KENWORTHY.
